UNITED STATES PATENT OFFICE.

JAMES H. ELLIOTT, OF MONTREAL, QUEBEC, CANADA.

DRAW-BAR.

SPECIFICATION forming part of Letters Patent No. 425,308, dated April 8, 1890.

Application filed December 23, 1889. Serial No. 334,708. (No model.)

To all whom it may concern:

Be it known that I, JAMES H. ELLIOTT, conductor, a subject of the Queen of Great Britain, residing at the city of Montreal, in the 5 Province of Quebec and Dominion of Canada, have invented certain new and useful Improvements in Draw-Bars, of which the following is a specification, reference being had therein to the accompanying drawings.

This invention relates to certain new and useful improvements in draw-bars now used for connecting railway cars or coaches on lines of railway, and has for its object to provide an improved draw-bar with means for 15 preventing the uncoupling and disconnection of the same in going around curves or in case of derailment of any of the forward cars of a train to prevent the complete destruction of the cars or coaches following by running 20 into the ditch. By ordinary constructions, when a train of cars is going around a curve in any line of railway, a sudden jerk or twist of the train or any of the cars is liable to unlock the draw-bars, or in the ordinary running of a train of cars around a sharp curve 25 in a line of railway the draw-bars will unlock, especially if the curve is any way sharp. I provide means for so locking the draw-bars that when a train of cars coupled together 30 thereby is rounding a curve, should the draw-bars become unlocked or from any cause become disconnected, the link or links which I employ would still hold the cars together until the dangerous part of the curve is passed, 35 and the force of the car or cars following the car or cars in front of the one so unlocked will shove the draw-bars together, and thus properly lock them again without stopping the train or causing any delay or damage to 40 life or property in so doing, as has been the case heretofore. While a train of cars is in motion any sudden check of the impetus will cause all these draw-bars in the train to lock of themselves without stopping the train for 45 that purpose, thereby saving a delay.

Other objects and advantages of the invention will appear in the following description, and the novel features of the invention will be particularly pointed out in the appended claims.

The invention is clearly illustrated in the

accompanying drawings, which, with the letters of reference marked thereon, form a part of this specification, and in which—

Figure 1 is a top plan illustrating the application of my improvement. Fig. 2 is a diagrammatic view, on an enlarged scale, illustrating the operation of my improvement.

Like letters of reference indicate like parts in both figures of the drawings.

Referring now to the details of the drawings by letter, A A represent portions of the frame-work of two railway-trucks to which my invention is applied.

B B are draw-bars, each connected at its 65 inner end, as at B', to one of the timbers of its respective truck. The outer adjacent ends of the draw-bars are of the ordinary spear-head form, as shown, and in the peculiar form of this operative or coupling end of the draw-bar I claim nothing new. In ordinary constructions with this class of couplers or draw-bars, in rounding curves, especially when the curve be a very sharp one, the draw-bars become unlocked or disconnected, and thus the 70 cars of the train are disconnected or separated and accidents are liable to happen therefrom. To guard against this is the object of my invention, and it is accomplished in the following manner:

C are links, there being one upon the upper side and one upon the lower side of the draw-bar. These links are attached at their ends to the heads of the opposite draw-bars, substantially at the center of the heads thereof. These links are connected at one end, as at C', upon a fixed pivot, and at their ends are each provided with an elongated slot C², through which the other pivot C³ passes.

The space between the platform and the 90 upper side of the draw-bar is very small, and the pin which is employed for connecting the couplers in place on the head of the draw-bars should be of such form that it will not interfere with the under side of the platform or 95 the upper side of the draw-bar, and so that it will not catch on the under side of the platform. The pins may be retained in place in any suitable manner—as, for instance, by means of a nut, which, when the pin is in 100 place, will be screwed up near the under side of the draw-bar, and a split pin may be intro-

duced to prevent the nut from working off from the shaking or jogging of the cars while in motion. Of course the nut will not require to be screwed up close and tight to the 5 under side of the draw-bar, as the draw-bar must be allowed sufficient room to play in from the motion of the cars. The operation will be readily understood.

When the cars are coupled, they are locked 10 by means of links with the pin C³, passed through the slots of the links, as shown. The links are designed to be removed at will and secured by use of a nut and split pin. The links are permanently fixed to one of the 15 heads of the draw-bar, and, being out of the plane thereof, will not interfere with the ordinary coupling of the cars. With the draw-bars thus connected, should the heads become unlocked or unfastened for any reason— 20 as, for instance, in going around a curve—they will be held together by the links, and the links will hold the draw-bars together and prevent separation of the cars. The slots provide for the ordinary play of the draw- 25 bars, so as to prevent injury or breakage of the links and allow the parts to more readily assume their normal position after the dangerous part of the curve is passed.

The impetus of the train will lock the draw- 30 bars, which become uncoupled while the train is in motion or passing around a curve. An ordinary coupling could be made to answer the purpose of the link intended for draw- bar. The links can be reversed on the draw- 35 bars at any time. Should the cars become

uncoupled, the links will hold the cars together safely.

If the cars run off the track while the train is in progress, although the draw-bars become unlocked, the cars will be prevented from running off into the ditch, although they might run along the ties of the track for miles, which has often been the case.

What I claim as new is—

1. The combination, with two opposing 45 draw-bars, of a link pivotally connecting the heads thereof and arranged to normally extend in an inclined direction relatively to the length of the draw-bars and extensible in the direction of its length, as set forth.

2. The combination, with two opposing draw-bars, of a link pivotally connected with the heads thereof and provided at one end with an elongated slot, substantially as shown, and for the purpose specified.

3. The combination, with two opposing draw-bars, of two links, one upon the upper and the other upon the under side of said draw-bars, pivotally connected at one end with the head of one of said draw-bars, and 60 at the other end provided with elongated slots, through which passes a pin connecting them to the other draw-bar, substantially as described.

In testimony whereof I affix my signature 65 in presence of two witnesses.

JAMES H. ELLIOTT.
